UNITED STATES PATENT OFFICE.

WILLIAM A. LORENZ, OF HARTFORD, CONNECTICUT.

DESIGN FOR A CAN OR JAR.

SPECIFICATION forming part of Design No. 35,069, dated September 10, 1901.

Application filed August 12, 1901. Serial No. 71,845. Term of patent 14 years.

To all whom it may concern:

Be it known that I, WILLIAM A. LORENZ, a citizen of the United States, residing in Hartford, in the county of Hartford and State of Connecticut, have invented a new and original Design for Cans or Jars, of which the following is a specification.

My design relates to the external contour of cans, jars, and similar receptacles.

In the drawings, in which similar numerals designate corresponding parts, Figure 1 is a top view, and Fig. 2 a side view, of a can or jar embodying my design.

The substantially cylindrical body 10 merges at its upper end, by means of the wide and slightly-inclined shoulder 11, into the comparatively short tapering zone 12, above which is the annular groove 13. That groove is approximately semicircular in cross-sec-

tional outline and is surmounted by the narrow and substantially cylindrical band or rib 14, which is somewhat smaller in diameter than the smallest portion of the zone 12, so as to present the appearance of a tapering top interrupted by the groove 13.

Having described my invention, what I claim as new, and desire to secure by Letters Patent, is—

The design for a can or jar substantially as shown and described.

In testimony whereof I have signed my name to this specification in the presence of two subscribing witnesses.

WILLIAM A. LORENZ.
